(57) **CLAIM**

The ornamental design for a baby balance bike, as shown and described.

DESCRIPTION

FIG. 1 is a perspective view of a baby balance bike showing my new design;

FIG. 2 is a front elevational view thereof;

FIG. 3 is a rear elevational view thereof;

FIG. 4 is a left side view thereof;

FIG. 5 is a top plan view thereof;

FIG. 6 is a bottom plan view thereof; and,

FIG. 7 is a perspective view in an alternative configuration. The broken lines in the baby balance bike illustrate portions of the baby balance bike that form no part of the claimed design.

The handle shown in broken lines in FIG. 7 represents environmental feature that forms no part of the claimed design.
